Application June 1, 1949, Serial No. 96,472

9 Claims. (Cl. 346—85)

1

This invention relates to improvements in time recorders wherein the attendance times of workers are recorded upon cards.

Briefly, the present invention is concerned with an attendance recorder of simplified construction and improved operation having automatic means for providing successive registrations upon an attendance record in conformance with a prearranged plan so that the record is accurately printed in a distinct pattern of impressions not subject to willful disfiguration or obliteration by the whim of a workman so inclined.

Many conventional attendance time recorders, for example, provide means of registration of an employee's coming and going times. Thus when a worker registers "in" at the start of his work day his attendance card shows his starting time printed upon an attendance card. Similarly when a worker finishes his work period and registers "out" a second printed registration is impressed upon his card showing his quitting time. When time is taken off for a lunch period similar "out" and "in" registrations are made upon the attendance card. The registrations above noted as to "in" and "out" may be said to be the normal authorized registration times, and provisions are made in the recorder to distribute such registrations over the card according to a preconceived arrangement so that the employee's wages may be easily and rapidly computed. In some establishments attendance recording machines are locked or disabled except at the so called authorized registration times. This practice, however, leads to confusion and dissatisfaction of employee and employer due to the irregular hours normally necessary to be worked in the modern factory or business establishment. Furthermore, late arrivals, those permitted to leave for sickness, those who work special schedules and shifts, overtime workers, and many others peculiar to the requirements of industrial production must be provided for in the furnishing of accurate attendance records. In order to so provide, various arrangements have been made in attendance recorders whereby registrations are printed upon an employee's card in different colors; for example, a registration made during one of the so called authorized times is printed in black while a registration made at other times is printed in red. Other arrangements provide a shift in the printed position of the attendance registration upon the card to distinguish irregular registrations from the regular ones. It is impracticable to provide an indefinite

2

number of printed colors or sufficient positions upon an attendance registration card to include each minute of the day; consequently, an employee may accidentally or intentionally overprint a registration upon his card thereby obliterating the true registration to the detriment of his employer, or of himself, or both. One such recording device is shown in U. S. Patent 1,848,218 wherein means is provided so that each registration is made in a different part of the attendance card; consequently, obliteration or interference with the true registration upon the card is eliminated.

In a recorder of the type above mentioned some means is generally provided whereby a perforation is made in the attendance card for each registration wherefrom the next registration may be located. Generally the locating mechanism includes a pin engageable with a perforation in the card so that if the card is manually withdrawn from a recorder so provided at the time of registration, a mutilated attendance card may result, either accidentally or intentionally.

The present invention is an improvement in card time recorders of the type just described. Not only is the present invention an improvement, but also a simplification in attendance recorder apparatus wherein a worker is unable to obliterate or to mutilate an attendance registration card either by accident or intent. The embodiment of the invention is carried out in a device provided to receive an attendance card by manual insertion into a slot forming a part of a receiver wherein a sensing element is provided to be engageably operated by a perforation in the card. The sensing element normally controls a contact making lever which, when operated through the continued advance of the inserted card, operates an electromagnet to cause a time registration to be printed at a predetermined position of the card normally referenced from the sensing element. Simultaneously with the printing of the registration a further perforation is also made in the card from which the next time registration may be referenced when the card is next inserted. Numerous modifications, later described herein, are provided to provide the initial registration and perforation in the card, to limit the overall registration field in the card, to provide interlocks for the machine's operation, to provide time controlled printing means, and to furnish program changes in the registrations according to a desired and predetermined schedule.

The principal object of this invention is to

provide an improved time recording machine for registering attendance time upon a card wherein the registration is effected solely by the insertion of a card whereby the registration is incapable of being obliterated and the card of being mutilated.

A further object of this invention is to provide an attendance time recorder of simplified construction and design.

Other objects of the invention will be pointed out in the following description and claims and illustrated in the accompanying drawings, which disclose, by way of example, the principle of the invention and the best mode which has been contemplated of applying that principle.

In the drawings:

Fig. 1 is a side elevation view of the machine with a portion of the cover broken away, certain of the mechanism being omitted from the top part of the machine for purposes of clarity.

Fig. 2 is a detail view of certain of the mechanism shown in Fig. 1, together with certain additional components of the top part that are omitted in Fig. 1.

Fig. 3 is a rear elevation view of the interior of the machine with certain parts removed to illustrate the insertion of a registration card in the card receiver.

Fig. 4 is a front elevation view of the interior of the machine with certain parts broken away.

Fig. 5 is a top view of the interior of the machine with certain parts removed.

Fig. 6 is a sectional view taken along the lines 6-6 of Fig. 5.

Fig. 7 shows an attendance registration card with normal registrations of attendance printed thereon.

Fig. 8 illustrates an attendance registration card wherein overtime registrations have been printed.

Referring to Fig. 1 a card receiver slot 10 is formed between two plates 11 and 12 extending substantially the length of the time recorder machine frame and of sufficient width (see Fig. 3) and thickness to permit the insertion of a registration card K such as illustrated in Fig. 6. Interposed in and along the path of the slot 10, in the order named, are a sensing finger 13, an abutting spring 14, a punch and die assembly 15, a platen 16, a knee toggle 17, and a projection 18a (or 18b or 18c, as later explained) upon a slide 19. A card guide 20 leads into the entrance of the receiver slot 10.

The finger 13 is hung by a spring 21 (see Fig. 2) to a ring 22 supported by the machine frame, and is further supported at its slotted portion 13a by a button stud 23. In addition to the provision of a spring support perforation 13b, the finger 13 has also a shoulder 13c and a right angle projection 13d. The spring 14 is fastened to the plate 11 by a pair of screws 14a and bent in such a manner that its tip projects through a hole in the plate 11 to slightly displace the end of the finger 13 when the latter is in its normal position. Thus it can be seen that the finger 13 is capable of sliding vertically upon the stud 23 against tension of the spring 21 or of being turned about the stud 23 acting as a pivot against the tension of spring 21.

The punch and die assembly 15 is composed of a punch 15p carried by a bar 24, through which the punch is actuated, and a die 15d mounted on the plate 12. Normally the punch 15p is in a retracted position as shown in Figs. 1 and 2. When actuated the punch 15p perforates the edge of a registration card K (see Fig. 2) which may

be occupying the slot 10 in the location of the assembly 15.

The platen 16 is also carried by the bar 24 by which it is actuated to press against a registration card K occupying the slot 10 through a cut out portion 25 of the plate 11 (see Fig. 3). Normally the platen 16 is also in a retracted position (note Fig. 5).

The knee toggle 17, again referring to Figs. 1 and 2, is pivoted upon a stud 26 and is capable of turning counterclockwise thereupon limited by its slotted cut 17a and a coacting stud 27 fixed to the machine frame. An ear 17b is formed upon the lower end of the toggle 17 and a knee 17c is formed on the left side of toggle 17. Normally when no card occupies the slot 10 as in Fig. 1 the knee 17c projects into a recess in plate 11 so that the ear 17b impinges upon the shoulder 13c and limits the sliding motion of the finger 13 when it tends to move downwards. When a card K occupies the slot 10 at the recessed portion of plate 11 as in Fig. 2, however, the toggle 17 is cammed by the card to be turned counterclockwise so that the ear 17b no longer engages the shoulder 13c thus permitting the finger 13 to move downwards.

The slide 19 (see also Fig. 3) is mounted upon plate 11 by two button screws 28 via two slotted portions 19b. Normally the slide 19 is biased to its upward position by a spring 29 fixed to an ear 19c and a stud 30 on the plate 11. On its upper end the slide 19 is provided with a bent over projection 19a, at its lower end with a similar projection 18a, and at its midsection with an extension which carries two other projections 18b and 18c, as shown in Fig. 3. All of these projections are inward through cut away portions of plate 11, and all of the projections except 18a are interposed into the slot 10 in such a way as to be encountered by a card which is inserted therein. In other words the slide 19 is operable by the insertion of a registration card K. If the card is of one length, as for example in Fig. 3, the slide will be operated by engagement of the card with the projection 18a in which event the projections 18b and 18c will be broken off to avoid interference with the card. If the card is of a shorter length only the projection 18c will be broken off and the slide 19 will be operated by engagement of the card with the projection 18b. For a card of still less length, no projections will be broken off and the slide 19 will be operated by engagement of the card with projection 18c.

Referring briefly to Figs. 1 and 3 it is to be noted that the die 15d opens into a cavity 31 wherein punched out fragments of a card are deposited by the travel of the punch 15p. Upon the outside of the plate 11 is a confetti container 32 for receiving these fragments, the container being detachably fastened by means of the spring clips 33 and 34 against the plate 11. It is essential that punched out paper fragments are retrieved in some manner so that the working parts of the recorder are not jammed thereby.

Now referring to Figs. 1 and 2 a slide 35 is hung to the plate 11 by a spring 36 connected to a stud 37 in the plate 11 and via the shoulder perforation 35a. The slide 35 is additionally supported via the elongated slots 35b and 35c by a button stud 38 and by a projection 38a upon a bell crank 39 which is supported by a stud 40 fixed to the side frame of the machine. The bottom of slide 35 normally rests upon a contact operating block 41 which when depressed closes a pair of electrical contacts 42 (note also Fig. 4). These con-

tacts are secured to the plate 12 which also supports via a yoke 43 an electromagnet 44 which is connected electrically in series with the contacts 42 to a suitable source of electrical supply. The slide 35 is fitted with a step at its upper extremity which cooperates with the projections 19a and 13d as hereinafter described. The bell crank 39 carries an arm 39b which when lifted pivots bell crank 39 counterclockwise causing the projection 39a to move the slide 35 to disengage its upper extremity from either of the projections 19a or 13d if engaged.

A solenoid plunger 45 is operated to be pulled upwards into the electromagnet 44 whenever the latter is energized. With continued reference to Figs. 1 and 4, bearings are provided in the side frames at 46 wherein a bearing rod 47 is supported. At each side of the recorder an operating arm 48 and an operating lever 49 are freely journalled at one of their extremities on the bearing rod 47. The other extremities of the levers 49 are fastened to a rod 50 which passes through a bearing 51 in the solenoid plunger 45 so that when the plunger is operated the levers 49 are pivoted clockwise about the rod 47. Near the center of each lever 49 is located a pivot stud 52 which forms a bearing support for a lever 53, there being one such lever on each side of the machine. A bearing stud 54 on each lever 53 supports the links 55 and 56 at one of their extremities. The other extremity of link 55 is pivotally supported upon a stud 57 on the arm 48 while the other extremity of link 56 is pivotally mounted upon a stud 58 on the side frame. (Note.—The links 55 and 56, and bearing studs 57 and 58 are duplicated on each side of the machine, see Fig. 4.) On the left side of the machine only, as viewed in Fig. 1, the lever 53 is provided with a knock-off tip 53a which coacts to lift the arm 39b. When the solenoid plunger 45 is pulled upwards by the electromagnet 44 the levers 49 rotate clockwise so that the studs 52 are raised thereby lifting the lever 53 and the stud 54 to pivot the link 56 counterclockwise and the link 55 clockwise. The aforesaid motion is all effected against the opposition of the springs 59 which are connected between the links 56 and fixed studs 60 on either side frame of the machine.

When the stud 54 is raised and the links 55 and 56 pivot, the arms 48 are thereby forced to rotate clockwise about the rod 47 so that the tops of these arms move to the right, as shown in Fig. 1, or toward the bottom of the sheet, as shown in Fig. 5. At the top end of each arm 48 a bearing pin 61 is inserted by which the yoke end 62a of a pull rod 62 is pivotally connected. The opposite ends 62b of the pull rods 62 are threaded and thereby fastened to the bar 24, which carries both the punch 15p and the platen 15, through bearings 63 mounted upon the side frames and abutting the plate 12 (see Fig. 5). It is apparent from Fig. 5, therefore, that when the tops of the arms 48 move toward the bottom of the sheet the pull rods 62 will operate the bar 24 to pull the platen 15 against a card that may occupy the slot 10 and likewise actuate the punch 15p to perforate the card.

Referring now to Figs. 2 and 5 an ink ribbon 64 is provided being stored upon spools 65 which are carried by the shafts 66 which are mounted in a sub-frame 67 attached to the plate 12. The sub-frame 67 also has mounted upon it a shaft 68 upon which suitably geared-together type wheels 69 are journalled which bear upon the ribbon 64 at the location of the platen 15 to enable

printed impressions to be made upon a card in slot 10.

A synchronous one revolution per minute electric clock motor 70 (see also Fig. 4) is mounted 5 on the sub frame 67 which has mounted upon its output shaft a cam 71 (see Fig. 2) which operates upon a cam follower 72 pivotally mounted upon the shaft 68 which also carries a locking arm 73 which is coupled to the follower 72 via an ear 73a, a spring 74, and a projection 72a. The free end of the arm 72 has pivotally mounted by a stud 72b thereon an operating pawl 75 which is normally held against a stop 76 by a spring 77 connected from the end of the arm 73 to a stud 78. The pawl 75 is adapted to engage the teeth of an advance gear 79, its travel being such that for each throw of the follower 72 the pawl 75 will advance the gear 79 one tooth. The gear 79 is coupled directly to the lowest order (minute) 15 type wheel 69. Hence each time the cam 71 makes one revolution the gear 79 will be advanced one tooth. A small gear 80 also freely mounted on the shaft 68 is directly connected to the gear 79. The gear 80 meshes with a gear 81 fixed on a shaft 82 carried in bearings on the sub-frame 67, and the gear 81 meshes with a gear 83 fixed on a shaft 84 which is connected with the hands driving gears of a clock indicator 85 mounted upon the top of the sub frame 67. This gearing is arranged to cause a minute hand 86 and an hour hand 87 to indicate the proper time upon the indicator 85.

As shown in Figs. 1, 4, and 5 the arm 48 on the left side of the machine (as viewed in Figs. 4 and 5) has an extension 88 attached to arm 48 by two screws 88a. The extension 88 is provided with a notched portion which engages an ear 89 upon a plate 90 which is slidably supported upon the shafts 66 by elongated slots 90a. A second ear 91 upon the plate 90 is connected by a spring 93 and a projection 92a to a bell crank 92 pivotally supported by a stud 95 in the sub frame 67. A yoke shaped bale 94 is pivotally supported by the stud 95 (and a similar stud not shown) and is provided with a projection 94a which is engaged 45 to be operated by a yoked portion of the bell crank 92. Each time the arm 48 is rocked about the bearing rod 47 the plate 90 (which controls the advance of the ribbon 64, the ribbon feed being of conventional pawl and ratchet design not shown) is reciprocated by the extension 88 so that the bell crank 92 is turned counterclockwise by the pull of spring 93 and the bale 94 is rotated counterclockwise. A series of detents 96 having equalizing springs 97 is carried by the bale 94 for engagement with the typewheels 69 to lock them in printing position whenever the platen 15 is operated to effect printing upon an attendance card. An extension 94b on the bale 94 is arranged 60 to engage the locking arm 73 to prevent jamming of the pawl 75 against the teeth of the ratchet gear 79 in the event that the follower 72 drops off the cam 71 at the instant that the solenoid plunger 45 is actuated.

Now referring to Figs. 2 and 4, a lever 98 is pivotally mounted at one end upon a stud 99 in the sub frame 67. Normally each time the follower 72 encounters the high point of the cam 71 a spring 100 mounted on the top of the follower 72 tends to force the lever 98 downwards (as viewed in Fig. 2). An arm 101 is rigidly attached to the lever 98. Connected to the end of arm 101 is a bale 102 extending at right angles therefrom across the faces of all of the type wheels 69 above the bale 94. A bale 104 is also carried by the fol-

lower 72, the bale 104 being parallel and above the bale 102. The bales 102 and 104 are supported at each end in a similar fashion (not shown) and an extension 103 on the bale 102 is arranged to control a pivoted pawl carried by the bale 104, similar to the pawl 75, so that the first said pawl is normally lifted away from engagement with the ratchet gear 105 over which it exercises control in a similar manner to that of pawl 75 over the gear 79. Whenever the lever 93 is lowered (rotated about stud 99 in a clockwise direction) the gear 105 is advanced by its pawl one tooth for each revolution of the cam 71. A type wheel 106 is directly fixed to the gear 105 so that for each alternate advance of the gear 105 by the aforesaid pawl an asterisk will be presented to the printing position under the platen 16 by the type wheel 106. Normally the tip 98a of the lever 93 rests upon the peripheries of a pair of discs 107 and 108 journaled on bearings mounted on a shaft 109. The disc 107 is directly fixed to a large gear 110 (see also Fig. 6) and the disc 108 is connected by a bushing to another large gear 111. The shaft 82 carries a pinion 112 which meshes with the gear 111. The shaft 82 also carries two single-toothed gears 113 and 114 having their single teeth displaced 180 degrees, each of the gears 113 and 114 alternately meshing with a Geneva gear 115, the gear 115 having the teeth in each half staggered or offset. The gear 115 is pinned to a shaft 116 journaled in a bearing 117 attached to the sub frame 67. The shaft 116 also has a gear 118 affixed which meshes with the large gear 110.

The discs 107 and 108 are each provided with a plurality of preformed "knock-outs" in their peripheries and the gear ratio of the gears 110, 111, 112, 113, 114, 115, and 118 are chosen accordingly so that by breaking out "knock-outs" such as 119 and 120 in the discs 108 and 107 respectively, the tip 98a of the lever 93 will be enabled to drop into the composite slot thus provided as the broken out "knock-outs" in the two discs match. Consequently, thereafter, when the high point of the cam 71 is next encountered by the follower 72, the bale 102 will be lowered and its extension 103 will no longer hold up the pawl which provides operation for the ratchet gear 105 and the type wheel 106 so that a change of character will then be printed in the next registration recorded by the machine at the printing position occupied by type wheel 106. This character change may be used to indicate whether the registration has been made during the normal authorized registration periods. For example, see the registration in the card K of Fig. 7 wherein the registration "DN TU AM 12:00" is during a regular period, thereafter a change in the program discs occurs, as described immediately above, following which the registration "DN * TU PM 1:02" is made. In this instance the "*" indicates that the registration was made in an off schedule or unauthorized period.

The automatic operation of the machine upon the insertion of an attendance card is as follows: With reference to Figs. 1, 2, 3, and 7 a card K is inserted into the slot 10. Let it be assumed that the card has no previous registration upon it and that it is of the maximum length usable in the machine so that the projections 18b and 18c have been broken off. As the card K is inserted in the slot 10 the tip 14b of spring 14 is cammed away from the card and the finger 13 bears against the other side of the card seeking to engage a perforation in the card. Since there are no perfora-

tions in this card at the moment, the card enters deeper into the machine camming the knee 17c of the toggle 17 aside and finally comes to rest with its leading edge upon the projection 18a of the slide 19. A further travel of the card K causes the slide 19 to move downward so that its projection 19a impinges upon the lower step of the top of slide 35 which is also moved downward against the block 41 thereby closing the contacts 42. A suitable electric power supply having been connected to the electromagnet 44 and contacts 42 leads, the electromagnet 44 is thereby energized and the solenoid plunger 45 is thereby actuated so that the bar 24 is operated via pull-rods 62, arms 48, links 55 and 56, levers 53 and 49, and the rod 50, as previously described. A registration will therefore be printed, as at the top registration in the card K of Fig. 7 by the platen 16 forcing the card against the ribbon 64 backed up by the type wheels 69 and 106. Simultaneously the punch 15p is forced through the card K against the die 15d and a perforation is made to the left of the printed impression as in the top registration of the card of Fig. 7. At the time that the solenoid plunger 45 operates to move the lever 53 upwards as previously described, the tip 53a lifts the arm 39b thereby causing the slide 35 to be cammed from under the projection 19a of slide 19, so that the slide 35 rises under the bias of spring 36 and the contacts 42 open deenergizing the electromagnet 44 and returning the punch, platen, pullrods, arms 48, and the associated linkages and levers to their normal positions under the bias of the springs 59. The card is then withdrawn and the slide 19 returns to its normal position urged by the spring 29.

Let it now be assumed that the card K is again inserted into the slot 10 in the same manner as before. Again the tip 14b of spring 14 is cammed away from the card and the finger 13 bears against the other side of the card seeking to engage a perforation. As the card travels deeper into the machine the toggle 17 is cammed aside as before and the perforation previously punched is now encountered by the finger 13 which enters thereinto and is forced downward so that its projection 13d impinges upon the top step of the top of the slide 35 which is again forced downward, as before, closing the contacts 42. Printing and punching operations are thereby effected as before; however, the registration is made in a position below the top registration of the card in Fig. 7. In a like manner as before the tip 53a of the lever 53 cams the slide 35 out from under the projection 13d releasing the slide 35 and opening the contacts 42.

Let it now be presumed that a registration has been made in the card K of Fig. 7 in the location of the dash line X—X, and that the card is inserted into the slot 10 of the machine as before. As in the last mentioned instance the finger 13 will engage and enter the perforation thereby being forced down as before. In this instance however, there is insufficient distance between the leading edge of the card K and the perforation (registration) along the line X—X so that the knee 17c is not encountered by the card to cam the toggle 17 out of the way. Hence the shoulder 13c engages the ear 17b of the toggle 17 and the downward travel of finger 13 is halted; consequently, no printing or punching results and no registration is made upon the card. In this manner the registration field of the card is determined and contained within the proper limits 75 of the card.

Fig. 8 illustrates registrations upon the reverse side of the card K corresponding to overtime registrations. Since the finger 13 encounters the card only along one longitudinal edge, the regular and overtime attendance registrations do not interfere with each other.

In the present invention as illustrated and described above, it is obvious that overprinting cannot occur. Furthermore it is equally obvious that since the punching operation is under the control of an electromagnet which operates the punch at very high speed and is automatically deenergized by its own operating linkages, i. e., the tip 53a, the arm 39b, and the slide 35, it is impracticable for one registering a card in the embodiment herein illustrated to mutilate or deface an attendance card in the machine itself. Consequently a very reliable and fool-proof registration device is provided.

While there have been shown and described and pointed out the fundamental novel features of the invention as applied to a preferred embodiment, it will be understood that various omissions and substitutions and changes in the form and details of the apparatus illustrated and in its operation may be made by those skilled in the art, without departing from the spirit of the invention. It is the intention, therefore, to be limited only as indicated by the scope of the following claims.

What is claimed is:

1. In a time recording machine for attendance cards the combination of means for receiving a card inserted thereinto and for guiding it along a predetermined path, printing means disposed along the said path, perforating means disposed along the said path coacting with the said printing means, means for simultaneously operating the said printing means and perforating means, means disposed in the said path for engaging a perforation previously made in the said card for relocating the card in said path, means under control of the said engaging means for actuating the said operating means, and means interposed in the said path operable by the said card for disabling the said engaging means.

2. In a time recording machine for attendance cards the combination of means for receiving a card inserted thereinto and for guiding it along a predetermined path, a series of type wheels carrying time indicating characters adjacent the said path, an ink ribbon interposed between the said characters and the said path, a movable platen disposed along the said path correlatively with the said characters and operable to force the said card against the said ribbon and the said characters to be printed, means for perforating the said card disposed along the said path, the said perforating means coacting with the said platen, means for simultaneously operating the said platen and the said perforating means, means disposed in the said path for engaging a perforation previously made in the card to relocate and to control the operation of the said perforating and printing means, means under control of the said engaging means for actuating the said operating means, and means interposed in the said path operable by the said card for disabling the said engaging means.

3. In a time recording machine for attendance cards the combination of means for receiving a card inserted thereinto and for guiding it along a predetermined path, printing means disposed along the said path, perforating means disposed along the said path coacting with said printing

means, means for simultaneously operating the said printing means and perforating means, means disposed in the said path for engaging a perforation previously made in the said card for relocating the card in the said path, means under control of the said engaging means for actuating the said operating means, and means interposed in the said path normally restraining the said engaging means, the said interposing means being card operated to release the said engaging means.

4. In a time recording machine for attendance cards, the combination of means for receiving a card inserted thereinto and for guiding it along a predetermined path, a series of type wheels carrying time indicating characters adjacent the said path and an ink ribbon interposed between the said characters and the said path, a movable platen disposed along said path, correlatively with the said characters and operable to force the said card against the said ribbon and the said character to be printed, means for perforating the said card disposed along the said path, the said perforating means coacting with the said platen, means for simultaneously operating the said platen and the said perforating means, means disposed in the said path for engaging a perforation previously made in the card to relocate and to control the operation of the perforating and printing means, means under control of said engaging means for actuating the said operating means, and means interposed in the said path normally restraining the said engaging means, the said interposing means being card operated to release the said engaging means.

5. In a time recording machine for attendance cards the combination of means for receiving a card inserted thereinto and for guiding it along a predetermined path, printing means disposed along the said path, perforating means disposed along the said path coacting with the said printing means, means for simultaneously operating the said printing means and perforating means, means disposed in the said path for engaging a perforation previously made in the said card for relocating the card in said path, means under control of the said engaging means for actuating the said operating means, means interposed in the said path operable by the said card for disabling the said engaging means, and means under control of said operating means for interrupting the said actuating means to prevent immediate reoperation of the said operating means.

6. In a time recording machine for attendance cards the combination of means for receiving a card inserted thereinto and for guiding it along a predetermined path, a series of type wheels carrying time indicating characters adjacent the said path, an ink ribbon interposed between the said characters and the said path, a movable platen disposed along the said path correlatively with the said characters and operable to force the said card against the said ribbon and the said characters to be printed, means for perforating the said card disposed along the said path, the said perforating means coacting with the said platen, means for simultaneously operating the said platen and the said perforating means, means disposed in the said path for engaging a perforation previously made in the card to relocate and to control the operation of the perforating and printing means, means under control of the said engaging means for actuating the said operating means, means interposed in the said path for engaging a perforation previously made in the card to relocate and to control the operation of the perforating and printing means, means under control of the said engaging means for actuating the said operating means, means interposed in

11

the said path operable by the said card for disabling the said engaging means, and means under control of said operating means for interrupting the said actuating means to prevent immediate re-operation of the said operating means.

7. An attendance time recorder comprising a card receiver into which an attendance card may be inserted and guided along a predetermined path, printing and perforating means disposed along the said path for affecting the said card, a solenoid for simultaneously operating the printing and perforating means, a finger disposed in the said path operable by engaging a perforation in the said card, a spring controlled by said card normally controlling the said card finger in the said path, a slide coacting with the said finger, a switch for controlling the said solenoid, said switch being operable by the said slide, and a toggle disposed in the said path normally restraining operation of the said finger the said toggle being operated by the said card to release the said finger.

8. An attendance time recorder comprising a card receiver into which an attendance card may be inserted and guided along a predetermined path, printing and perforating means disposed along the said path for affecting the said card, a solenoid for simultaneously operating the printing and perforating means, a finger disposed in the said path operable by engaging a perforation in the said card, a spring controlled by said card normally controlling the said card finger in the said path, a slide coacting with the said finger, a switch for controlling the said solenoid, said switch being operable by the said slide, a toggle disposed in the said path normally restraining operation of the said finger, the said toggle being operated by the said card to release the said finger, and a bell crank con-

trolled by said solenoid for disengaging the said slide from the said finger to prevent re-operation of said solenoid.

9. An attendance time recorder comprising a card receiver into which an attendance card may be inserted and guided along a predetermined path, printing and perforating means disposed along the said path for affecting the said card, a solenoid for simultaneously operating the printing and perforating means, a finger disposed in the said path operable by engaging a perforation in the said card, a spring controlled by said card normally controlling the said card finger in the said path, a slide coacting with the said finger, a switch for controlling the said solenoid, said switch being operable by the said slide, a toggle disposed in the said path normally restraining operation of the said finger, the said toggle being operated by the said card to release the said finger, and a card slide engageable by the edge of said card cooperating with the said slide to operate the said switch when no perforation is engaged by the said finger.

ALFRED L. SPRECKER.
